United States Patent Office.

JOHN F. H. KING, OF PORT RICHMOND, NEW YORK.

Letters Patent No. 82,849, dated October 6, 1868; antedated September 25, 1868.

IMPROVEMENT IN SIGNAL-FLAGS FOR VESSELS.

The Schedule referred to in these Letters Patent and making part of the same.

TO ALL WHOM IT MAY CONCERN:

Be it known that I, JOHN F. H. KING, of Port Richmond, in the county of Richmond, State of New York, have invented a new and useful Improvement in the Manner of Hanging or Setting Signal-Flags, suitable particularly for use on board vessels, and which I call "The American Lloyd's Signal-Setter;" and that the following is a full, true, and exact description of my said improvement, reference being made to the drawings accompanying, and making part of this, my specification.

Figure I, of the drawings, represents a side view or elevation of my improvement, and of the signal-flag, hung at the mast-head.

Figure II represents the frame or setting, without the flag attached, in the position required for setting or displaying the signal, the dotted lines showing the position of the frame or setting when the flag is not set or displayed, and when being hoisted or lowered.

The same letters represent the same parts in both the figures.

The practice of designating vessels by signal-numbers upon flags or signals, so as to be recognized when vessels pass each other at sea, or approaching or leaving port, is well known. The number which characterizes or designates the vessel being affixed upon the signal-flag in clear and distinct color, and the number being registered in the shipping-lists, and published in the Marine Register, or Reports of Vessels, the display of the signal-flag indicates the name of the vessel to all who may have lists for reference; and where the system of numbering each vessel is carried out, and generally adopted and published, as in the case of the New York Marine Register, or American Lloyd's Register of American and Foreign Shipping, vessels passing each other at sea may be recognized readily, and with certainty of finding the signal-number upon the book or register. But, when the signal-flag is simply fastened at one end to the mast, staff, or the halyard, it is oftentimes difficult, and occasionally impossible, to read distinctly the number upon the signal, owing to the fluttering and waving of the flag in the wind, and in a calm, the flag drops and folds by its own weight, so that the numbers cannot be read.

It is to obviate this inconvenience that my improvement is directed, and which I accomplish in the manner now to be described.

I construct a frame, composed of two sticks or pieces of wood, of suitable size and length for the length of the end and upper edge of the flag. One of these pieces, *a*, Figs. I and II of drawing, constitutes the staff of the signal-flag, the other piece, *b*, constitutes a support or stretcher for the upper edge of the flag. The two frame-pieces *a* *b* are united near the upper end by a pin passing through the two pieces, and holding them together, and at the same time forming a joint, by which the piece *b* readily turns, so as to lie close alongside of the piece *a*, or to stand at right angles to it. At the upper end of the staff *a* is an eye, for fastening the halyard *c*, by which the frame and flag are suspended to the mast. The inner end of the piece *b* is also provided with an eye, *d*, to which is fastened the line or halyard *e*, by which the outer end of piece *b* is to be raised or lowered. The line *e* is brought down and passed through an eye or ring, *f*, inserted in the lower part of staff *a*.

The signal-flag is fastened at the two interior corners and at the exterior upper corner, so as to be readily inserted in the frame or taken out, as described. The two ends *c* *d* of the frame-piece *a* *b* are connected by a small chain or cord, *g*, of such length as to permit the frame-piece *b* to be drawn or raised to a position at right angles to the piece *a*, by the hauling of the line or halyard *e*, and to hold it in that position when required.

When the signal-flag is to be set or displayed, the halyards *c* *e* are hauled taut, and the ends secured to the cleat *h* upon the mast. By this arrangement the staff *a* is held steady in a vertical position, and the frame-piece *b*, extending the length of the flag in a horizontal position, holds it out its length, so as to display the number on the flag, in wind or calm.

When the signal is not in use, the halyard *e* is loosened, when the frame-piece *b* turns upon the pivot, and falls close alongside of *a*, folding the flag, and the whole can then be reefed compactly together.

For the more readily being distinguished at a distance, the numbers on the flag should be red on a white ground, or white on a red ground.

The frame-piece *b* may be connected with staff *a* by a cord placed on the outer ends, so as to limit the rising of *b* to a right angle with *a*, instead of using the short chain *g*, but this plan is not so convenient as that above described. Other devices, such as a shoulder or slotted joint, may answer the purpose of the chain or cord, so as to arrest and stay the arm *b* at the proper point, but I prefer the chain or cord.

Having thus described my invention, what I claim therein, and for which I desire Letters Patent, is—

The constructing and combining the two frame-pieces *a* *b* and the check-chain or cord *g* with the halyards, for displaying or folding a signal-flag, the whole arranged and operating substantially in the manner and for the purposes described.

JOHN F. H. KING.
